M. E. LEE

SPIKE PULLER

Filed Nov. 10, 1923

INVENTOR
MARGARET E. LEE

BY

Harry P. Schweder
ATTORNEY

UNITED STATES PATENT OFFICE.

MARGARET E. LEE, OF OAKLAND, CALIFORNIA.

SPIKE PULLER.

Application filed November 10, 1923. Serial No. 672,930.

To all whom it may concern:

Be it known that MARGARET E. LEE, a citizen of the United States, residing at Oakland in the county of Alameda and State of California, has invented certain new and useful Improvements in Spike Pullers, of which the following is a specification.

My invention is an improved spike puller, particularly applicable for removing the spikes from railroad ties.

The object of my invention is to provide a spike puller which will grip the spike at any point on the shank, thereby drawing the spike from the wood without bending it, thus enabling said spike to be re-used.

Another object is to provide a spike puller, which is simple in construction, and inexpensive to manufacture.

Referring to the annexed drawing in which my invention is illustrated:

Figure 1 is a side view of my spike puller.

Figure 2 is an enlarged fragmentary side view of the same.

Figure 3 is a fragmentary front view of my spike puller.

Figure 4 is a bottom view of the same.

Figure 5 is a sectional view taken on the line 5—5 of Figure 4.

Figure 6 is a fragmentary front view of my puller with the jaws removed.

Figure 7 is a view similar to Figure 3, with the jaws raised and spread.

Figure 8 is a rear view of one of the jaws.

Referring more particularly to the drawing, the elongated handle 1 has an angularly positioned chisel 2 at one end and a pair of arms 3 and 4 at the other end thereof. The lower edges of the arms 3 and 4 are curved as at 5 and they meet at the rear to form the heel 6. The inner surfaces of the arms 3 and 4 each converge downwardly, the purpose of which will be further described.

A pair of jaws 7 and 8 are positioned between the arms 3 and 4, and are pivoted on a bolt 9 which extends through the arms. 45 A bolt 10 extends through the arms 3 and 4 and through slots 11 in the jaws 7 and 8, thus limiting the vertical movement of the jaws. A spring 12 is positioned between the handle and the jaws 7 and 8 to urge the 50 jaws downwardly. The outer walls of each of the jaws 7 and 8, which contact with the inner surfaces of the arms 3 and 4, diverge upwardly as shown at 13, which is opposite to the slope of the said arms. Thus when 55 the jaws are moved upwardly against the spring 12, they will follow the inner surfaces of the arms 3 and 4 and spread apart as shown in Figures 4 and 7 and grip the spike at a new point. The lower surfaces 60 of the jaws 7 and 8 are curved as at 14 to conform with the curve 5 of the arms 3 and 4. In operation the handle 1 is moved forward to backward on the surface 5 to raise and lower the jaws 7 and 8 as described. 65 These jaws are each provided with spike engaging recesses 15 on the adjacent edges thereof.

Having described my invention, I claim:

A spike puller comprising an elongated 70 handle, a pair of arms formed on the lower end of said handle, a pin between the arms, and a pair of jaws having apertures therethrough pivoted between said arms and a spring engaging the rear of said jaws to 75 urge them downwardly, each of said jaws having slots formed therein and a second pin between the arms extending through said slots, and into the arms, to limit the movement of said jaws.

In testimony whereof I affix my signature.

MARGARET E. LEE.
